UNITED STATES PATENT OFFICE.

EDWARD A. THIELEN, OF DORRANCE, KANSAS.

HOIST.

Application filed August 5, 1925. Serial No. 48,383.

The invention relates to an improved hoist more particularly adapted for use in garages, machine shops and factories for the purpose of quickly and safely raising automobiles, trucks, etc., in order that the mechanical parts thereof may be conveniently accessible to the workman or inspector.

One of the more particular objects of this invention is to provide a substantial, inexpensive, efficient and durable hoisting means adapted to be operated by compressed air or liquids, such power supplying means usually being regular equipment in practically all places where the hoist would be used.

Another object of this invention is to provide a means of the class described, arranged and designed to be installed below the floor in such manner that, when inoperative, the device does not in any manner interfere with regular work above the floor, and when in operation only a limited number of parts extend above the floor, thereby greatly reducing the annoyance, to workmen, of bulky and interfering parts usually found in devices of this nature which have come to my attention.

A further object of this invention is to provide a hoist of the class described which is disposed to operate entirely by a "pushing up" action, thereby wholly eliminating danger to life and property incident to the breaking of chains, etc.

It is a further general object of the invention to provide a hoist for the above purpose consisting of relatively few parts which are all of simple construction in order that the device may be produced at comparatively small manufacturing cost.

With the above and other objects in view, my invention further consists in the novel features of construction, combinations and arrangement of parts and units, all of which will be first fully described in the following detailed description and illustrated in the accompanying drawings. It is to be understood, however, that the form chosen for illustration may be modified without departing from the spirit of the invention as expressed in the claims.

In the drawings:—

Figure 1 is a side elevation of the stationary unit of my hoist.

Figure 2 is an end elevation of the stationary unit of the hoist.

Figure 3 is a plan view of the stationary unit of the hoist.

Figure 4 is a side elevation of the sliding unit of the hoist.

Figure 5 is an end elevation of the sliding unit of the hoist.

Figure 6 is a somewhat diagrammatic side elevation of the hoist assembled for use, the same being shown with the sliding part thereof elevated.

Figure 7 is an end elevation of the hoist assembled for use, the same being shown with the sliding part thereof elevated.

Figure 8 is a detail vertical cross section of the lower end of the operating cylinder.

Figure 9 is an enlarged detail horizontal section taken on the line 9—9 on Figure 7.

Referring in detail to the drawings, Figures 1, 2 and 3, the upright members 1 and 2 of the stationary unit are formed in a channel shape from heavy sheet steel and are rigidly maintained in position by cross angles 3 at the lower ends and centers and by the cross angles 4 at the tops.

To prevent deflection or buckling of the members 1 and 2, the sheet steel brace plates 5 and 6 are securely attached to the same and to the cross angles 3 and 4 by means of bolts or rivets 7.

At the bottom of the unit, angles 8 are provided as means for a support or rest, and are disposed to be securely fastened to the floor of the pit or basement.

The top angles 4, as will be noticed, extend a distance beyond the uprights 1 and 2 and are intended to be attached to the main floor of the garage or shop, thus rigidly supporting the top section of the unit. It is clearly obvious, it is thought, that proper anchoring of angles 4 and 5 will provide for ample rigidity of the unit.

An air chamber or cylinder 9 is provided and maintained in upright position between metallic heads 10 and 11 through the medium of four stay rods 12, and this whole combination is securely attached to the cross angles 3, of the unit, by bolts 13, any suitable means 14 being provided to prevent the escape of air from between the ends of the cylinder 9 and the heads 10—11. The cylinder head 11 is provided with an opening to permit passage of the piston rod or pipe 15, the lower end of which is attached to the piston head 16, the opposite end of the piston rod being connected with the lifting plate 17 which in turn is attached to the cross member 18 of the sliding unit. See Figures 4 and 6.

2 Referring to Figures 4 and 5 illustrating the sliding unit it will be observed that channel steel vertical slide members 19 are provided and are connected intermediate 5 their ends by the cross channel iron 18 through the medium of corner brackets 20 and bolts 21. A parallel relative position of the members 19 is assured by means of the brace pipes 22 secured as at 23 to the members 18 and 19. In order that accurate adjustment of members 22 may be made, each 10 said member is provided at each end respectively with a right and a left hand screw thread, the support castings 23 being 15 threaded likewise.

The wheel rest castings 24 are attached to the upper ends of members 19 by means of bolts 25 and are designed to conform generally to the periphery of automobile or 20 truck wheels, thereby preventing movement of an automobile or truck being raised or lifted.

A knowledge of the detailed construction 25 of the air cylinder 9 and piston 16 may be had by reference to Figure 8 in which 9 designates the cylinder proper, the lower end of which is maintained in engagement with the head 10 by means of stay bolts or rods 12. A short distance from the end of 30 the piston rod or pipe 15 is located a nut 26 adapted to engage the upper one of the plates 27-28 contributing in formation of the piston lead 16. The leather gasket or 35 ring 29 is firmly held between the members 27 and 28 by means of the nut 30.

As will be noticed, the edge of the gasket 29 extends for a distance below section 28 and is formed in such manner that a close 40 contact with the cylinder wall is maintained. When air pressure to the cylinder is admitted, the tendency of the gasket 29 to extend outwardly is increased, thereby making the escape of fluid pressure between the cylinder wall and gasket practically impossible.

The cylinder head 10 is provided in the center with a boss 31 adapted to engage the end of the piston rod or pipe 15 on the downward movement, thereby preventing the gasket 29 from coming in contact with 45 said head. Fluid pressure is admitted to the cylinder at the lower end only through the medium of the pipe 32 which is connected to a supply line 33 from a tank 34 or other source of supply. The pressure is 50 controlled by a suitable three-way valve 35 spliced in the line 33. The first position of the valve lever admits fluid to the cylinder which raises the sliding member of the hoist to the desired height, the second position of 55 the valve lever will cut off the flow of pressure to the cylinder, thus allowing the sliding member to remain stationary in an elevated position, and the third position of the valve lever permits the fluid within the 60 cylinder to escape and permit the hoist to

move downwardly to its at rest position. The cylinder 9 may be made from any kind of substantial metal material, but seamless brass or steel tubing is preferable.

In the drawings, Figure 9, I have shown 70 a cross sectional view illustrating the co-operative relation of the guides 1 and 2 and slides 19-19. It will be observed that metal wear and guide strips 36 may be secured to the insides of the guides 1 and 2 by the bolts 75 37. By providing the metal strips 36 the edges of the slide channel members 19 of the sliding unit are prevented from coming in contact with the rounded portions or sections of the members 1 and 2, thus avoiding 80 increased friction at these places. It will also be noticed that the heads of the bolts 37 serve as a guiding means for the members 21.

Again referring to Figures 6 and 7, 88 83 designates the floor of the building in which the hoist is installed. A section 39 should be removable to permit access to the mechanical parts of the hoist. The side walls 90 of the pit in which the device is placed are designated 40 and the lower floor or foundation for supporting the hoist should be of concrete or other suitable substantial nature.

It should be clearly obvious that the fluid 95 pressure supply tank and control valve may be placed at any convenient point about the premises.

From the foregoing description, taken in 100 connection with the accompanying drawing, it is thought the novel details of construction, manner of operation and advantages of my invention will be readily apparent to those skilled in the art to which it relates.

What I claim is:

1. A device of the class described comprising, a stationary unit including vertical guide standards, a cylinder, a plunger and piston vertically movable in the cylinder, means for admitting fluid pressure to move said piston, means for controlling said fluid pressure; and a vertically movable unit secured to the plunger to move therewith and having vertical members slide-guided in 110 said guide standards and adapted when moved to lift or lower an article to be lifted or lowered, said vertical guide standards having wear strips bolt-secured thereto, said bolts being positioned for having their heads 115 act as retaining mediums for the slide-guided vertical members.

2. A device of the class described comprising, a stationary unit including vertical guide standards, a cylinder, a plunger and piston vertically movable in the cylinder, means for admitting fluid pressure to move 125 said piston, and means for controlling said fluid pressure, and a vertically movable unit secured to the plunger to move therewith 130

and having a pair of vertical members slide-guided in said guide standards and adapted when moved to lift or lower an article to be lifted or lowered, said slide-guided vertical member each having a cupped head secured at its upper end for the purposes specified.

3. A device of the class described comprising, a stationary unit including vertical guide standards, a cylinder, a plunger and piston vertically movable in the cylinder, means for admitting fluid pressure to move said piston, and means for controlling said fluid pressure; and a vertically movable unit to be moved by said plunger for lifting and lowering articles to be lifted and lowered, said movable unit comprising vertical members slide-guided by said guide standards, a cross bar joining the vertical members intermediate of their ends and to which the plunger is secured, and adjustable diagonal braces secured to the cross beam and each vertical member for the purposes specified.

4. A device of the class described comprising, a stationary unit including vertical opposed channel guide standards, upper, lower, and intermediate brace angles secured to the standards, a cylinder, top and bottom closure plates for the cylinder, stay bolts securing the plates and cylinder as a unit, bolts securing the plates to the lower and intermediate brace angles to secure the cylinder in upright position, a piston operable in the cylinder, a plunger secured to move with the piston and extending just above the intermediate brace angles when at its low-

ered position, means for admitting fluid pressure to move said piston, and means for controlling said fluid pressure; and a vertically movable unit secured to the plunger to move therewith and having vertical members slide-guided in said guide standards and adapted when moved to lift or lower an article to be lifted or lowered.

5. A device of the class described comprising, a stationary unit including vertical opposed channel guide standards, upper, lower, and intermediate brace angles secured to the standards, said upper brace angles being extended to facilitate securing of the device to the bottom of an operating floor, feet secured to the standards and extended to facilitate securing of the device upon a supporting base floor, a cylinder, top and bottom closure plates for the cylinder, stay bolts securing the plates and cylinder as a unit, bolts securing the plates to the lower and intermediate brace angles to secure the cylinder in upright position, a piston operable in the cylinder, a plunger secured to move with the piston and extending just above the intermediate brace angles when at its lower position, means for admitting fluid pressure to move said piston, and means for controlling said fluid pressure; and a vertically movable unit secured to the plunger to move therewith and having vertical members slide-guided in said guide standards and adapted when moved to lift or lower an article to be lifted or lowered.

EDWARD A. THIELEN.
